UNITED STATES PATENT OFFICE.

EDWARD Y. MOORE, OF EVANSTON, ILLINOIS.

DRIVE-CHAIN LINK.

SPECIFICATION forming part of Letters Patent No. 316,992, dated May 5, 1885.

Application filed February 6, 1885. (Model.)

To all whom it may concern:

Be it known that I, EDWARD Y. MOORE, residing at Evanston, in the county of Cook and State of Illinois, have invented certain new and 5 useful Improvements in Drive-Chain Links, of which the following, in connection with the accompanying drawings, is a specification.

In the drawings, Figure 1 is a face or top view of two of my improved links connected together. Fig. 2 is a vertical section of the links, taken on the line $x x$ of Fig. 1. Fig. 3 is a face or top view of the links detached; and Fig. 4 is a side view of two of the links, showing the position in which they may be connected together.

15 My invention relates to that class of drive-chain links in which the links are attachable together or detachable by hand when held in a certain position; and the object of my invention is to provide a neat and strong link of small cost and easy to manufacture, all of which I will hereinafter describe.

Like letters of reference indicate like parts.

A A are drive-chain links. These links may 25 be made either of cast or malleable metal, and each consists of two side bars, B B, and of two end bars, C and C'. The end bar C is continuous and extends from one side bar to the other, as shown.

30 a a are disk-like extensions projecting in the longitudinal direction of the side bars from those corners of the link which the bar C connects, and a' a' are studs or comparatively short cylindrical parts extending from the inner faces of the disks or extensions a a.

D is a tongue extending from the bar C, and having a depression or socket, b, and projecting out between but not uniting the parts a' a'. The bar C is adapted to enter the hook or socketed tongue D.

40 E E are hook-like or socketed extensions formed on the bar C', or at its junction with the side bars. The sockets or depressions b' b' in the parts E E are curvilinear in the same direction as the hook D is, as shown. By having at each end of the link the sockets or hooks similarly curved and in the form of about half a circle or less than half a circle upward or downward, as may be deemed most desirable, I am enabled 45 to cast the link in a comparatively easy manner.

The inner ends of the hooks E E are re-enforced or strengthened by webs or flanges c c, which are continuous with the end bar C'.

The outer rims of the hooks E E are not flush with the outsides of the bars B B, room being 55 thus provided, as shown at d d, to receive the extensions a a when the links are arranged together, as shown, so that the said extensions will then be flush with the outer lines of the chain; but these recesses d d are not absolutely 60 necessary. I also gain or cut the recesses d d with a slope, e, as shown in Fig. 3. Having the recesses so sloped allows the links to be brought together or formed into a small angle—about thirty-five or forty degrees—for the purpose of putting them together or taking them apart.

To use or put together the links A A, they are placed in the position shown in Fig. 4, when the bar C' on one link may be placed in hook D 70 on the other. The studs a' a' will also at the same time slip into the hooks E E, and by turning the upper link so as to be in a horizontal line with the other one they will be securely connected. With more links and successive 75 operations of the same kind a continuous chain may be formed. To undo them, one link is turned over so as to form an angle of about thirty to forty degrees with lower one, and then lifted upward, when they will come apart. 80

It will be seen that when two of my links are placed together the end bar C on one link and the studs a' a' on the other form the journal or pivotal joint or connection between the links, while the hook D on one and the 85 hooks E E on the other form the central bearings for pivotal action. It will also be seen that two of the links cannot be parted laterally or sidewise, that their construction is simple, and that they form together a very neat and strong 90 drive-chain.

A very important feature of my invention is, that the hooks or sockets are all formed in about the shape of half a circle or less than half a circle. This half-circular form of the 95 sockets or hooks permits the pivotal parts of a link to be inserted therein without a movement sidewise, as in many links that have hooks or sockets more than half-circular in form. This construction admits of a transposition of 100 parts; but I would regard any mere transposition of parts as within the scope and principle of my invention.

Having thus described my invention, what I claim as new, and desire to secure by Letters 105 Patent, is—

A drive-chain link consisting of side bars, B
B, and end bars, CC', the bar C having thereon
a hook-shaped tongue, D, and the bar C' hav-
ing at each end thereof the hook-shaped ex-
tensions or sockets E E, the side bars, B B, hav-
ing at their ends which are connected by the
bar C extensions a a, on which are the cylin-
drical studs a' a', projecting toward but not
meeting the hook D, substantially as and for
10 the purposes set forth.

In testimony that I claim the foregoing as
my own I hereto affix my signature in presence
of two witnesses.

EDWARD Y. MOORE.
